UNITED STATES PATENT OFFICE.

LEO BRAND, OF NEW YORK, N. Y.

SMOKEHOUSE.

Application filed February 16, 1928. Serial No. 254,885.

This invention relates to smoke houses, an object of the invention being to provide within a smoke house an improved construction for supporting and imparting rotary motion 5 to a frame supporting meats to be smoked.

A further object is to provide a smoke house of this character with an improved construction of rail and rail support which insures the proper centering of a hanger supporting the basket relative to a rotary shaft supporting the track whereby the basket is properly centered and maintained in such relationship during the rotary motion imparted thereto.

15 A further object is to provide an improved support and coupling means between the track in the smoke house and the track outside of the smoke house on which the hanger and basket can be moved to any desired point 20 or from any desired point.

25 A further object is to provide improved electrically operated means for imparting rotary motion to the hanger and basket and control said circuit through the medium of one 30 of the doors of the smoke house so that rotary motion cannot be imparted until the doors are securely closed.

With these and other objects in view, the invention consists in certain novel features of 35 construction and combinations and arrangements of parts which will be more fully hereinafter described and pointed out in the claims.

In the accompanying drawings—

35 Figure 1 is a view in longitudinal section through the smoke house;

Figure 2 is a top plan view of the smoke house;

40 Figure 3 is a fragmentary view in vertical transverse section on the line 3—3 of Figure 2;

Figure 4 is a fragmentary view looking at the upper front portion of the smoke house;

45 Figure 5 is a fragmentary view in section on the line 5—5 of Figure 4;

Figure 6 is a sectional perspective view looking from the interior of the smoke house and showing the supporting means for the smoke house track;

50 Figure 7 is a fragmentary view in front elevation looking from the front of the smoke house and showing the position of the track and hanger relative thereto.

1 represents a smoke house proper which 55 may be made of any suitable material but is

preferably of sheet metal suitably lined and packed and provided in its lower portion with a burner 2. A channel bar 3 is secured from the top of the smoke house 1 and extends transversely thereof and supports a bearing 4 through which a vertical shaft 5 extends into the smoke house, this shaft being located centrally relative to the top of the smoke house. An arched bracket 6 is fixed to the bar 3 and also has a bearing for the shaft 5, and a ring or head 7 is fixed to the upper end of the shaft and holds the shaft against downward movement.

Between the head 7 and the bracket 6 washers 8 may be located to properly space 70 the parts, and similar washers 9 may be located between the bearing 4 and a beveled gear wheel 10 secured to the shaft 5. Motion is transmitted to the gear wheel 10 by means of a beveled pinion 11 meshing therewith. 75 This pinion 11 is secured on a shaft 12 mounted in bearings 13 and 14 in the bracket 6 and in a bracket 15. The shaft 12, as a matter of fact, constitutes two aligned sections connected by a clutch 16 which is controlled by a lever 17 pivotally supported between its ends, as shown at 18, on a bracket 19 fixed to the bar 3.

Motion is transmitted to the shaft 12 through the medium of an electric motor 20 supported on top of the smoke house, the 85 shaft 21 of said motor operating to turn a sprocket wheel 22.

In Figures 2 and 4, I illustrate a casing 23 which represents a gear reducing casing containing a suitable arrangement of reducing 90 gears so that the speed of the motor is reduced and the sprocket wheel 22 is turned at the desired speed. This sprocket wheel 22 is connected by a sprocket chain 24 with a sprocket wheel 25 on one of the members of clutch 16. 95

The front of the smoke house 1 is normally closed by a pair of hinged doors 26 and 27, the door 26 having an overlapping bead 28 which overlaps the edge of the door 27 to effect a tight closure. The door 27, which 100 closes first and opens last, has a finger 29 thereon adapted to engage an electric switch arm 30 located at the upper and front portion of the smoke house and pivotally supported in a box or casing 31. 32 is a coiled spring 105 which normally holds the switch arm in position to open the circuit to the motor 20, as clearly shown in Figure 5.

When the door 27 is closed its finger 29 will force the switch arm 30 to a position to close 110

the circuit and impart rotary motion to the shaft 5 projecting through the top of the smoke house. 33 represents a block or casting which is firmly secured to the lower end of shaft 5 and located in the upper central portion of the smoke house. The block 33 has a base flange 34 on which an angle rail 35 is rigidly secured.

The rail 37 where it is supported on the block 33 has its upper edge downwardly inclined, as shown at 38, and is provided with a stop or abutment 39 so that a wheeled carrier 40 mounted to run on the track 37 will ride down the incline and against the abutment 39 so as to properly center the carriage relative to the shaft and maintain the carriage in this position during the rotary motion imparted thereto.

The wheeled carriage 40 supports a basket 41 adapted to contain meat to be smoked, and this basket may of course be made in any suitable manner but will be of a size to turn freely within the smoke house 1.

I refer to the member 41 as a basket although it is sometimes called a frame, cage, tree or other terms but to avoid repetition I shall refer to the same as a basket.

The rail 37 is of a length to extend to a point adjacent the front wall of the smoke house, and to support this free end of the rail while the carriage is passing over the same I provide a depending bar 42 secured to the inner face of the front of the smoke house 1 and this bar 42 at its lower end has a ledge 43 integral therewith and having at least one inclined or tapering end 44 on to which the free end of the rail 37 rides, and is supported in its position of alignment with a track or rail 45 outside of the smoke house, as shown in Figures 1 and 2 of the drawing.

This rail or track 45 may of course extend to any desired point or points and is spaced from the front of the smoke house. The gap between the rail 45 and the rail 37 is closed by a track section 46 pivotally connected at one end to the track 45, as shown at 47, and having a finger 48 at its free end.

The rail 37 at its free end is notched, as shown at 49, to receive the finger 48, and plates 50 are secured to the opposite sides of the rail 37 so as to confine the rail section 46 between them when said section couples the aligned rails 45 and 37.

It is to be understood of course that there is sufficient lateral play of the pivot 47 to allow the section 46 to uncouple and fall by gravity to the position shown in Figure 1, and as indicated in Figures 4, 6 and 7 of the drawing, the front of the casing has an opening 51 therein of a size to accommodate the wheeled carrier 40. This opening is closed by the doors 26 and 27, as indicated in Figure 4.

In operation, the loaded cage 41 suspended from the wheeled carrier 40 is run along the track or rail 45, and assuming that the doors

of the smoke house are open and the track section 46 coupled to the track or rail 37, the wheeled carrier and basket can be run into the smoke house. As the wheeled carrier moves along the track 37 it will ride down the incline 38 and come to a stop against the abutment 39 so as to properly center the same relative to the shaft 5. When the track section 46 is uncoupled and allowed to swing downwardly to the position shown in Figure 1 the doors of the smoke house can be closed, and as the door 27 is closed it will close the electric circuit and start the motor. The clutch 16 controlled by the lever 17 can then be thrown into operation and rotary motion imparted to the basket. When the tracks or rails 37 and 45 are in alignment it will be noted that the ledge 43 will sustain the weight of the free end of the rail 37, and this weight will be sustained until the carrier reaches a position of suspension on the block 33, as clearly shown in Figure 1.

When the operation is ended, the track 37 is aligned with the track 45, and this may be accomplished by a slight manual movement, 90 the track section 46 then being moved to bridge the gap between the rails and the wheeled carrier and basket can be moved out of the smoke house to any point desired.

My improved smoke house has many advantages, not only from the fact that it insures a proper centering of the wheeled carrier and basket but it prevents accidental movement from this position, and the rail supporting the carrier is provided with a support for its free end so that there will be no sagging or dropping of the track when the carriage passes over the free end thereof.

Furthermore, with my improved smoke house, after the carriage or carrier is run into the smoke house, it can be turned manually and the operation can be observed by opening one of the doors.

While I have illustrated what I believe to be a preferred embodiment of my invention it is obvious various changes and alterations might be made in the general form of the parts described without departing from my invention and hence I do not limit myself to the precise details set forth but consider myself at liberty to make such changes and alterations as fairly fall within the spirit and scope of the appended claims.

I claim:

1. A smoke house, having a shaft projecting through the top thereof, a block secured to the shaft, a rail secured to the block and having an inclined upper edge and an abutment at its extremity whereby a wheeled carrier on said rail is directed by gravity to a centralizing position on the block, and a track outside of the smoke house adapted to align with the first mentioned rail.

2. A smoke house, having a shaft projecting through the top thereof, a block secured

to the shaft, a rail secured to the block and having an inclined upper edge and an abutment at its extremity whereby a wheeled carrier on said rail is directed by gravity to a centralizing position on the block, and a ledge in the casing supporting the free end of said rail when said rail is alined with a rail outside of the casing.

3. A smoke house, having a shaft projecting through the top thereof, a block secured to the shaft, a rail secured to the block and having an inclined upper edge and an abutment at its extremity, whereby a wheeled carrier on said rail is directed by gravity to a centralizing position on the block, a rail outside of the smoke house spaced from the smoke house, a ledge in the smoke house adapted to support the free end of the first mentioned rail, and a pivoted track section connected with the outer rail and adapted to

couple to the first mentioned rail to bridge the gap between them.

4. In a smoke house, the combination with a rotary block in the top thereof, a rail supported by said block, a wheeled carrier adapted to run on said rail and support a basket, an abutment on said rail against which the carrier engages to center the carrier relative to the block, a track outside of the casing spaced from the smoke house, a movable track section adapted to bridge the gap between said last mentioned rail and the first mentioned rail, and means for supporting the free end of the first mentioned rail when said rail is in position for alinement with the rail outside of the casing.

Signed at New York, in the county of New York and State of New York this 14th day of February, A. D. 1928.

LEO BRAND.
